UNITED STATES PATENT OFFICE.

OSCAR C. SCHMIDT, OF CINCINNATI, OHIO, ASSIGNOR TO THE CINCINNATI BUTCHERS' SUPPLY COMPANY, OF CINCINNATI, OHIO, A CORPORATION OF OHIO.

KNOCKING PEN.

Application filed August 15, 1927. Serial No. 213,158.

It is the object of my invention to provide a new and improved knocking pen of simple construction and of few parts, and so arranged that the knocked animal will be automatically discharged from the pen; further, to provide novel means whereby a movable floor in knocking pens is dispensed with; and, further, to provide an improved knocking pen comprising flanged bars and metal sheeting so formed as to strengthen the frame of the pen and to discharge the collapsing animal from the side of the pen.

The invention will be further readily understood from the following description and claims, and from the drawings, in which latter:

Fig. 1 is a front elevation of my improved device.

Fig. 2 is a plan view of the same.

Fig. 3 is a front end elevation of the same.

Fig. 4 is a rear end elevation of the same.

Fig. 5 is a horizontal section of the same, taken on the irregular line 5—5 of Fig. 4; and,

Fig. 6 is a vertical central section of the same, taken on the line 6—6 of Fig. 1.

The frame of my improved device comprises angle iron corner posts 11, the tops of which are connected at the front and rear of the frame respectively by angle iron longitudinal stringers 12, 13, and at the ends of the frame respectively by angle iron cross stringers 14, 15. The middle portions of the posts are, at the front and rear of the frame, respectively connected by longitudinal angle iron stringers 16, 17. A rear lower longitudinal angle iron stringer 18 connects the rear posts near their bottoms. The bottoms of the post are, at the respective ends of the frame, connected by plates 19, 20, secured respectively at their ends to one of the wings of angle iron feet 21, 22, in turn secured respectively to the lower ends of the uprights. These cross-strips rest upon the floor 23, which may be the killing floor of the slaughter house, and present no obstruction to the passage of the animal into and out of the ends of the pen.

Rear metal sheets 25 extend across the upper portion of the rear wall of the pen, the margins of the sheets being secured to the longitudinal stringers 13, 17, and the rear posts. The upper portion of the front wall of the pen is closed by a metal sheet 26, the margins which are secured to the vertical

wings of the longitudinal stringers 12, 16, and the corresponding wings of the front uprights.

The lower portion of the rear wall comprises steel sheeting 31, which includes a downwardly forwardly sloping wall 32, and endwise outwardly and rearwardly sloping ends 33, 34, which are bent from the downwardly, forwardly sloping portion of sheeting along bends 35, 36, at the ends of said downwardly, forwardly sloping portion of said sheeting. This arrangement forms said downwardly forwardly sloping portion of said sheeting with downwardly and forwardly converging ends.

The upper margin of said downwardly forwardly sloping sheeting is secured to one of the wings of the rear longitudinal stringer 17, and the rear ends of said endwise outwardly and rearwardly sloping ends are fixed to the proximate wings of the rear posts of the frame.

In order to further strengthen said downwardly forwardly sloping portion of the rear wall, the rear face of said sheeting has an angle iron 37 fixed thereto, one of the wings of which is fixed to said sheeting and the other of the wings of which projects rearwardly therefrom. Angle iron brackets 38 are fixed crosswise to the rear angle iron stringer 18. One of the wings of these angle iron brackets are partly cut away at their front ends to form flanges 39, which are bent slantingly upward parallel with and under the rearwardly projecting wing of the angle iron brace 37, for reinforcing said downwardly and forwardly lower portion of said rear wall. The said wings are rigidly fixed together.

The upper portions of the ends of the frame are provided with cross plates 41, 42, respectively rigidly fixed to the upright posts at the respective ends of the frame. This leaves spaces 43, 44, at the respective ends of said frame for the passage of cattle.

The fabricated flanged bars and the plates and sheeting, which may be steel sheeting, are rigidly secured together in any suitable manner, as by means of rivets, nuts and bolts, or by being welded together, electrically or otherwise.

An operator's platform 51 is secured to the front wall of the framing, as by having its inner end fixed to one of the wings of the longitudinal stringer 16. Supporting

hangers 52, in the form of strips, are secured to the outer portions of the respective ends of the platform and to the end front corner posts above the platform.

5 The end spaces in the end walls of the pen are preferably arranged to be closed by gates 55, 56. These gates are of similar construction, and respectively comprise cross-bars 57, 58, to which a closing sheet 59 is secured, a bracing bar 60 fixedly connecting the cross-bars. The cross-bars and the bracing bar are preferably formed of angle iron. Hinge brackets 61 are fixed to one of the corner posts, a hinge rod 62 being received through holes in the horizontal wings of the cross-bars and holes in said hinge brackets for hinging the gate.

10 Each of the gates is provided with latch bars 65, 66, hinged to the gate on bolts 67, 68, and connected by a link 69 hinged to said bars by bolts 70, 71. The link is provided with an operating handle 72. Said bars reciprocate under straps 73, 74, fixed to the plate 59. The latch bars coact with 15 gate keepers 75, 76, which are fixed to the end upright post, for receiving the latch bars and closing the gate.

15 The animal to be knocked is admitted to the pen through one of the gates and stands on the killing floor. The operator stands on the platform and knocks the animal through the top of the pen. The animal in collapsing falls against the lower end of the rear wall, which slopes forwardly and 20 downwardly at its middle portion, and the knocked animal is thereby projected through the lower portion of the front wall of the pen.

25 This normally open lower portion is below the platform 51. The upper portion of this space is normally closed by a door 81, which comprises a sheet of metal 82 across which hinge straps 83 are fixed. These hinge straps have hinge eyes 84 at their upper ends. A hinge rod 85 is received through these hinge eyes and through holes in angle iron brackets 86 fixed to the longitudinal stringer 16. An angle iron bracing strip 87 extends longitudinally across the lower margin of the metal sheet of the door. One of the wings of this angle iron strip and the lower margin of the metal sheet of the door are rigidly fixed together.

30 A latch-bar 91 is hinged to the door on a bolt 92. Straps 93, 94, are fixed to the door at the outside of the latch-bar. The ends of the latch bar reciprocate under said straps. Keepers 95, 96, for the latch-bar are fixed to the respective front posts at the ends of the pen. The latch-bar is provided with an extended handle 97. Moving the handle upwardly releases the latch-bar from the keepers and permits the swinging of the door. The lower end of the door 35 is provided with a latch 98, by means of

which it may be suspended from the platform 51 to hold the front door open.

The front door 81 may be employed for keeping the knocked animal, for instance, a bullock, in the pen, until he is ready to be 40 released for bleeding purposes, whereupon the front door is opened and the bullock released, the bullock sliding through the lower portion of the front wall of the pen. Said door may also be normally held closed, for 45 instance, in knocking smaller animals, in order to prevent the escape of such smaller animals through the front of said pen before the knocking takes place. When such smaller animals are knocked, they collapse 50 upon the forwardly sloping rear wall and are projected outwardly thereby.

55 Wherever parts are fixed together in my improved construction they may be either bolted or riveted together, or fixed together by electric or other welding.

60 My improved knocking pen is simple and economically made and provides a firm and strong structure for the purpose intended. The lower portion of the rear wall has its 65 ends sloped endwise outwardly and rearwardly for directing the animal to the front portion of the middle of the pen without danger of stumbling or injury to the animal, and compelling the animal to stand in such manner as to be most convenient for the operator, and for enhancing his automatic discharge from the pen and facilitating discharge of the animal feet-first 70 through the front wall of the pen.

75 Having thus fully described my invention, what I claim as new, and desire to secure by Letters Patent, is:

1. A knocking pen comprising a frame 80 built up of fabricated flanged bars and metal sheets, said frame comprising a front wall and a rear wall, the lower portion of said rear wall comprising metal sheeting whose upper edge is substantially in the plane of 85 said rear wall and which slopes downwardly and forwardly toward said front wall of said frame and has end portions which slope oppositely endwise outwardly and rearwardly toward the plane of said rear wall along 90 bends at the ends of said downwardly and forwardly sloping portion of said rear sheeting, which bends converge downwardly, the rear margins of said end portions fixed to the rear of said frame, and an operator's 95 platform along the front of said front wall, the lower portion of said front wall provided with a discharge opening opposite 100 said downwardly and forwardly sloping portion of said sheeting for discharge of the knocked animal.

105 2. A knocking pen comprising a frame built up of fabricated flanged bars and metal sheets, said frame comprising a front wall and a rear wall, the lower portion of said rear wall comprising metal sheeting whose 110

upper edge is substantially in the plane of said rear wall and which slopes downwardly and forwardly toward said front wall of said frame and has end portions which slope 5 oppositely endwise outwardly and rearwardly toward the plane of said rear wall along bends at the ends of said downwardly and forwardly sloping portion of said rear sheeting, which bends converge downwardly, 10 the rear margins of said end portions fixed to the rear of said frame, an operator's platform along the front of said front wall, the lower portion of said front wall provided with a discharge 40 opening opposite said downwardly and forwardly sloping portion of said sheeting for discharge of the knocked animal, a gate extending across the upper portion of sail opening below said platform and hinged at 45 its upper portion to said front wall so as to swing upwardly under said platform, means for latching said last-named gate to said front wall, and means for latching said front gate to said platform. 50

4. A knocking pen comprising a frame built up of fabricated flanged bars and sheet metal, said frame comprising a front wall and a rear wall, the lower portion of which rear wall comprises metal sheeting whose upper edge is substantially in the plane of said rear wall and which slopes downwardly and forwardly toward said front wall and has end portions fixed to said frame, a flanged bar extending lengthwise of said sloping portion and fixed to the rear face of said downwardly and forwardly sloping portion intermediate of the height of said downwardly and forwardly sloping portion, a longitudinal stringer fixed to said frame in rear of said sloping portion above the lower end of said sloping portion, and cross brackets fixed to said longitudinal stringer and coacting with said flanged bar for reinforcing said downwardly and forwardly 60 65 70 sloping metal sheeting.

In testimony whereof, I have hereunto signed my name.

OSCAR C. SCHMIDT.
